UNITED STATES PATENT OFFICE.

MATTHEW F. COON, OF BOSTON, MASSACHUSETTS.

IMPROVEMENT IN SHOE-HORNS.

Specification forming part of Letters Patent No. **222,020**, dated November 25, 1879; application filed October 3, 1879.

To all whom it may concern:

Be it known that I, MATTHEW F. COON, of Boston, county of Suffolk, and State of Massachusetts, have invented a certain new and useful Improvement in Shoe-Horns, of which the following specification, when taken in connection with the accompanying drawings, is such a full, clear, and exact description as will enable others skilled in the art to make and use the same.

In said drawings, Figure 1 represents a plan view of my improved shoe-horn when ready for use. Fig. 2 is a plan view of the same when closed, and Fig. 3 is a cross-section of the same when closed.

This invention relates to the construction of shoe-horns, either of metal, gutta-percha, celluloid, or any suitable material, in such a manner as to be readily closed together, so as to occupy about one-half or one-third of the usual length, making it very convenient for those wishing such an article always ready for use when traveling.

Referring to the drawings, the part marked A is the end usually inserted in the heel of the shoe. B is the middle part, and C is the

handle. *a a a* are small square or oblong blocks, made fast to A and B, and standing up from their surfaces, so as to reach through the slots *b b b*, which are made in B and C, and are provided with heads to keep the parts B and C from coming off, yet allowing them to slide freely back and forth.

The part B may be dispensed with, if desired, when, as will be readily seen, there need be but one block or rivet, *a*, and one slot, *b*, when the two parts A and C will be connected in the same manner as the two parts B and C are now connected, making a shoe-horn, when closed, that may be conveniently carried in the pocket.

Having thus fully described my invention, I claim—

As an improved article of manufacture, a shoe-horn consisting of a series of connected plates adapted to slide one upon the other, substantially as shown, for the purpose stated.

MATTHEW F. COON.
